UNITED STATES PATENT OFFICE.

GEORGE M. EAMES AND ALEXANDER LAUBSCHER, OF BRIDGEPORT, CONNECTICUT, ASSIGNORS TO WHEELER & WILSON MANUFACTURING COMPANY, OF BRIDGEPORT, CONNECTICUT, A CORPORATION OF CONNECTICUT.

SEWING-MACHINE BASE.

SPECIFICATION forming part of Letters Patent No. 740,256, dated September 29, 1903.

Application filed May 7, 1903. Serial No. 156,110. (No model.)

To all whom it may concern:

Be it known that we, GEORGE M. EAMES and ALEXANDER LAUBSCHER, citizens of the United States, residing at Bridgeport, in the county of Fairfield and State of Connecticut, have invented a certain new and useful Improvement in Sewing-Machine Bases, of which the following is a full, clear, and exact description.

10 In the use of ordinary flat-bed sewing-machines, especially those that are power driven, it is oftentimes desirable to have the work travel around the cloth-plate without hindrance to its movements. Power-driven sewing-machines have to be freely oiled, and it is quite necessary to protect the work from the dripping oil.

15 It is the object of this invention to provide for these and other contingencies; and to this end the invention consists of a base upon which the sewing-machine is mounted in such way as to be capable of being turned over, as upon a hinge, for giving access to its under works, and which base affords the necessary 25 means to enable the work to be moved around the cloth-plate without hindrance and also serves as a drip-pan or oil-receptacle to catch the dripping lubricant.

20 In the accompanying drawings, illustrating the invention, in the several figures of which like parts are similarly designated, Figure 1 is a perspective view of the base detached. Fig. 2 is an end elevation showing a flat-bed sewing-machine hinged to the base and tilted over sidewise, a portion only of the sewing-machine being shown and that in dotted lines. Fig. 3 is a perspective view showing the base applied to an approved form of power bench or stand for sewing-machines.

30 The base may be and preferably is a metal casting of trough-like form comprising a substantially flat floor 1, provided with screw-holes 2 or other means for securing it in place upon a stand, and vertical walls 3, 4, and 5, rising from opposite sides and at one end, and a curved lateral projection 6, having an end wall 7. The wall 3 of the base and that portion of the projection continuous thereof is provided with a substantially horizontal ledge 8, which may have sockets to receive the or-

dinary hinge members of a sewing-machine or may be supplied with sockets composed of metal plates 9, bolted or otherwise secured to the ledge 8, with any suitable noise-deadening or cushioning devices 10 interposed, rubber, felt, leather, and the like being suitable for this purpose. The plates 9 are provided with transverse slots 11 to coöperate with the complementary hinge members 12 of the sewing-machine 13. (See Fig. 2.) The opposite 55 wall of the base is supplied with cushions of rubber, felt, leather, or other material 14 to receive the opposite edge of the bed of the sewing-machine. The wall 4 may be supplied with a screw 15 to engage a flange on the sewing-machine or a hole in such flange to hold the sewing-machine firmly upon the base.

60 As shown in Fig. 3, the base has its flat portion secured to a portion 16 of the table, while the lateral projection overhangs the 70 usual opening in the table, so that when the sewing-machine is mounted upon said base the work may be moved around the base and the machine without hindrance.

75 The parts shown in Fig. 3 and not particularly described are well-known power appliances in common use, and therefore need no further description here.

80 As indicated in Fig. 2, the sewing-machine may be hinged to this base and movable thereon in the ordinary way.

85 The base not only serves as such for the sewing-machine, but it also serves as an oil-receptacle or drip-pan to catch the lubricant dropping from the sewing-machine and prevent it from soiling the work.

90 The projecting end of the base affords an unbroken edge for the material to travel over when stitching endless strips or skirts or in cording endless strips and in hemming pillow-cases and other articles that have to be fed around the cloth-plate of the sewing-machine.

95 From the foregoing it will be apparent that the base admits of the use of a flat-bed sewing-machine for many, if not substantially all, purposes usually requiring a cylinder sewing-machine.

What we claim is—

1. A sewing-machine base of trough-like form, having a main portion provided with a 100

bottom, side walls, and an end wall, and a laterally-projecting curved portion also having an end wall, combined with a table or stand having its top cut out beneath the said 5 curved portion to permit the work to be passed freely about said curved portion.

2. A sewing-machine base of trough-like form, having a main portion provided with a flat bottom, parallel side walls, and an end 10 wall, a laterally-projecting curved portion also having an end wall, and a substantially horizontal ledge extending along one side of

the main portion and the curved portion and having hinge members, the lateral projection of the curved portion permitting the work to 15 be freely passed around it.

In testimony whereof we have hereunto set our hands this 6th day of May, A. D. 1903.

GEORGE M. EAMES.
ALEXANDER LAUBSCHER.
